AUTOMATIC HEADLIGHT DIMMER FOR AUTOMOBILES

Arthur G. B. Metcalf, Milton, Mass., assignor to Electronics Corporation of America, Cambridge, Mass., a corporation of Massachusetts

Application September 23, 1959, Serial No. 57,648

Term of patent 14 years

(Cl. D14—6)

Fig. 1.

Fig. 2.

Fig. 3.

Fig. 4.

Fig. 5.

Fig. 1 is a top plan view of an automatic headlight dimmer for automobiles embodying my new design;
Fig. 2 is a side elevational view;
Fig. 3 is a bottom elevational view;
Fig. 4 is a rear elevational view; and
Fig. 5 is a front elevational view.

I claim:

The ornamental design for an automatic headlight dimmer for automobiles, as shown.
